UNITED STATES PATENT OFFICE.

ALEX GULLBERG, OF ARLINGTON, NEW JERSEY, AND CHARLES L. SMITH, OF NEW YORK, N. Y.

JOGGING ATTACHMENT FOR SIGNATURE-GATHERING MACHINES.

1,090,473.

Specification of Letters Patent. Patented Mar. 17, 1914.

Application filed June 12, 1912. Serial No. 703,160.

To all whom it may concern:

Be it known that we, ALEX GULLBERG and CHARLES L. SMITH, citizens of the United States and residents of Arlington, in the county of Hudson, State of New Jersey, and the city of New York, borough of Manhattan, in the county of New York and State of New York, respectively, have invented certain new and useful improvements in Jogging Attachments for Signature-Gathering Machines, of which the following is a specification.

The object of our invention is to provide a new and improved jogging attachment for signature gathering machines, which is simple in construction and which automatically takes the signatures for a complete book, as gathered by the signature gathering machine, from the conveyer of such signature gathering machine and gradually turns the book of gathered signatures through an arc of 90° thereby placing it on edge, upon a suitable platform and while so placing it on edge jogs the several signatures so that they will be properly and perfectly alined, ready for lifting off the machine and which attachment is simple in construction, reliable and quick in operation and is strong and durable.

In the accompanying drawings in which like letters of reference indicate like parts in all the figures: Figure 1 is a side view of our improved jogging attachment for signature gathering machines. Fig. 2 is a plan view of the same. Fig. 3 is a detail perspective view of one of the rock shafts provided with the book supporting rods.

The shaft 1, mounted in suitable brackets 2, at the end of the gathering machine carries at one end a sprocket wheel 3 over which a sprocket chain 4 is passed which is driven from the main shaft of a gathering machine so that when the gathering machine is in operation the shaft 1 is rotated in the direction of the arrow. Of course, it will be understood that any other suitable motion transmitting means may be provided for driving the shaft 1 at a speed proportionate with that of the signature gathering machine. On the shaft 1 two circular plates 5 are rigidly secured and in the rims of these two circular plates a series of transverse shafts 6 are mounted to rock, there being nine such shafts 6 in the particular embodiment here illustrated. Each shaft 6 projects

beyond the circular side plate 5 opposite the one adjacent to the sprocket wheel 3 and on the projecting end of the shaft an arm 7 is secured which at its free end carries a roller 8 which can run on the edge of a fixed cam 9 secured in one of the brackets 2, so that this cam is in a permanent relation to the circular structure formed by the side plate 5 and connecting shafts 6 mounted therein. A spring 10 is attached to each arm 7 and to the hub of the corresponding plate 5 as at 11 so as to press the rollers 8 of the arms 7 of the several shafts 6 against the rim of the cam as the circular structure is rotated in the direction of the arrow. The cam 9 as shown is concentric with the shaft 1 for the greater part of its circumference but part of its circumference is provided with eccentric parts 12 and 13 and on part of its rim the cam is provided with a series of projections 14 alternating with recesses.

On each shaft 6, a sleeve 15 is secured which is provided with flanges 16 and 17 at right angles to each other and in said flanges two sets of arms 18 and 19 are formed which consist of rods, the rods of each pair crossing each other at right angles and there are preferably three such pairs of crossing arms 18 and 19 on each shaft 6. As the circular structure rotates the longer arms 18 are substantially in horizontal position when they are near the conveyer guide 20 of well-known construction of the sheet gatherer and the arms 19 will be vertical so that the book of signatures delivered from the conveyer of the signature gathering machine rests snugly in the rectangular frame formed by the arms 18 and 19 and as this frame or holder moves upward with the rotating circular frame, the book of signatures is gradually carried through an arc of 90°, the signatures being guided at one edge by the corresponding curved side wall 22 extending from the side wall of the conveyer guide of the book gathering machine upward and then extended horizontally as shown at 23. As the signatures comprising the gathered book gradually pass into the vertical position and rest with their bottom edges on the shorter arms 18 on the shafts 6, the rollers 8 of the arms 7 on the shafts 6 pass over the projections 14 and are thus moved forcibly up and down which vibrates the frame or support formed by the crossed rods 18 and 19, which vibra-

tions cause the jogging of the loose sheets and causes them to come into proper and perfect alinement.

The roller 8 after leaving that part of the cam edge provided with projections 14 slides down the eccentric part 12 and the cam thereby turns the corresponding shaft 6 in such a manner that the rods 19 stand vertically and the arms 18 horizontally by which time the book has been conveyed upon the part 23 of the horizontal platform 26 and rests against the yielding vertical follower 27 on said platform 26 or against a gathered book previously delivered upon the platform 26 and resting against the follower 27. The corresponding frame composed of the crossed rods 18 and 19 moves downward when the corresponding cam roller 8 travels upon the eccentric part 13 of the cam, which serves to hold and maintain the corresponding rods 19 in vertical position, while they are sliding down until their upper ends have passed beneath the horizontal plane of the platform 25 and then the rollers 8 gradually run upon the concentric part of the rim of the cam and thereby the arms 19 on the shafts 6 are gradually swung downward and then upward so as to be in horizontal position when they again move up to the platform 20 upon which the books have been delivered by the conveyer of the gathering machine and so on. As the supporting frames composed of the rods 18 and 19 move down vertically when leaving the gathering book of signatures, which book now stands vertically on the platform 25, they cannot have any disturbing or disarranging effect whatever upon the jogged signatures comprising the book and they do not jar the same, but deliver them in perfect manner upon the platform 25-26. The follower 27, which is movable on the platform 25-26 stands vertically on the same and is connected with a cord or rope 28 which passes over guide pulleys 29 and 30 and carries a weight 31 at its lower end, which serves to press the follower 27 toward the left.

The gathered books of signatures are thus automatically removed from the conveyer guide of the signature gatherer, are automatically placed on edge while being carried through an arc of 90°, are jogged while resting on edge and are delivered ready for removal without subjecting the signatures to any disarranging jars or shocks.

32 is a curved retaining guide for the side edges of the signatures and is suitably secured to one of the brackets 2 or a rigid and fixed part of the machine.

Having described our invention, what we claim as new and desire to secure by Letters Patent is:-

1. The combination with the signature conveyer guide of a signature gathering machine, of a rotary structure, supports carried

by the said structure for carrying piles of gathered signatures, and means for vibrating said supports while carrying said piles of gathered signatures, substantially as set forth.

2. The combination with the signature conveyer guide of a signature gathering machine, of a rotary structure, supports on said structure for carrying piles of gathered signatures, a fixed platform upon which the piles are delivered by the said supports, said platform being at a higher elevation than the conveyer guide of the signature gathering machine, and means for vibrating the book supports in their passage from the plane of the conveyer guide to the said platform, substantially as set forth.

3. The combination with the signature conveyer guide of a signature gathering machine, of a rotary structure, right angled book supports mounted pivotally on said structure, a fixed cam, adjacent to which cam the said structure rotates, and tilting arms connected with the supports and acted upon by the cam, and means for vibrating the book supports in their passage from the plane of the conveyer guide to said platform, substantially as set forth.

4. The combination with the conveyer guide of a signature-gathering machine, of a rotary structure, rocking shafts on the same, signature supports on said rocking shafts, a fixed cam adjacent to the rotary structure, and arms on the rocking shafts traveling on said cam, and means for vibrating the book supports in their passage from the plane of the conveyer guide to said platform, substantially as set forth.

5. The combination with the conveyer guide of a signature-gathering machine, of a rotary structure, a rigid supporting platform at a higher elevation than the conveyer guide, supports on the rotary structure for conveying piles of gathered signatures from the conveyer guide to said supporting platform and to bring them from a horizontal to a vertical position, a fixed cam adjacent to the rotary structure and means for controlling the positions of said supports on the rotary structure by said cam, and means for vibrating the book supports in their passage from the plane of the conveyer guide to said platform, substantially as set forth.

6. The combination with the conveyer guide of a signature gathering machine, of a rotary structure, a series of rocking supports on the same for piles of gathered signatures, a horizontal platform adjacent to said structure and on a higher plane than the conveyer guide, a fixed cam mounted concentrically with the rotating structure and provided on its edge between the end of the conveyer guide and the beginning of the elevated platform, with undulations and tilting

means carried by the pivoted supports, engaging the edge of the cam, substantially as set forth.

7. The combination with the conveyer 5 guide of a signature gathering machine, of a rotary structure, a series of rocking supports on the same, for piles of gathered signatures, a horizontal platform adjacent to said structure and on a higher plane than the conveyer guide, a fixed cam mounted concentrically with the rotating structure and provided on its edge between the end of the conveyer guide and the beginning of the elevated platform with undulations and tilting

means carried by the pivoted supports engaging the edge of the cam, said cam having eccentric parts in that part of its rim along which the supports travel when moving downward, substantially as set forth.

Signed at New York city, in the county 15 of New York and State of New York, this 29 day of March, A. D. 1912.
